UNITED STATES PATENT OFFICE.

LYNN A. WILLIAMS, OF EVANSTON, ILLINOIS.

TYPE-WRITER KEYBOARD.

992,316.

Specification of Letters Patent.

Patented May 16, 1911.

Application filed October 10, 1908. Serial No. 457,043.

To all whom it may concern:

Be it known that I, LYNN A. WILLIAMS, a citizen of the United States, residing at Evanston, in the county of Cook and State 5 of Illinois, have invented a certain new and useful Improvement in Type-Writer Keyboards, of which the following is a full, clear, concise, and exact description, reference being had to the accompanying drawings, forming a part of this specification.

My invention relates to keyboards for use with typewriters and it is an object of my invention to provide a means by which the keys constituting the main portion of the 15 keyboard may be readily distinguished from extra keys used in connection with some styles of typewriting machines.

In connection with typewriters generally it has been the practice to use an arrangement of keys in which the combination of 20 the characters indicated upon the key heads and corresponding to the characters adapted to be operated by the keys is known as the "universal" keyboard. This keyboard has, 25 after years of experimentation, been decided upon as one of the most efficient arrangements of the characters for practical use, and is an arrangement commonly used in connection with so-called "touch" systems 30 of typewriting. In these systems the location of the hands of the operator upon the keyboard is determined by the relation of the fingers to the end ones of the several rows of keys, selection of all of the keys on 35 the keyboard being determined by proper movements of the hands of the operator relatively to the certain normal positions determined by such end keys without requiring the operator to look at the keyboard to 40 ascertain whether such selection is correct.

In connection with some types of machines it has been found desirable to use extra characters and extra keys corresponding to such characters. These keys have usually 45 been placed at the ends of the several rows of keys normally used in connection with the typewriter, and an undesirable result of this arrangement has been that an operator familiar with the touch system of 50 typewriting is seriously confused because the hands naturally locate themselves upon the keyboard with reference to the end keys of the several rows. By my invention I avoid this difficulty by locating the extra keys at a 55 different height than the remaining keys in the corresponding rows, as a result of which

they are not naturally touched by the operator in locating the hands on the keyboard by the touch system. This arrangement, however, offers practically no difficulty to using these extra keys, since they may be operated when desired quite as readily as though they were on the same level as the remaining keys on the corresponding rows.

While my invention is particularly adapted to use with the so-called "universal" keyboard to distinguish the keys composing it from extra keys that may be used, it is equally applicable to any standard keyboard arrangement in which a certain combination of characters or letters has been commonly employed and with which it is found desirable to use in some cases extra keys and characters.

The several drawings illustrating my invention are as follows: Figure 1 is a plan view of a typewriter keyboard. Fig. 2 is a front view of the keyboard shown in Fig. 1, and shows the location of the end keys relatively to the remaining keys of the several rows. Figs. 3 and 4 are detail views of two of the keys and key bars.

Similar numerals refer to similar parts throughout the several views.

As shown in the drawings, the framework 11 of the typewriter supports in any suitable manner not shown a plurality of key bars terminating in several rows of keys 1, 2, 3 and 4. These rows of keys are situated at different heights relatively to each other, the back row 1 being the highest, the row 2 immediately in front of the first row being somewhat lower, the row 3 in front of the row 2 being lower still, while the row 4, or 90 the front row, is lower than the row 3. This is the usual arrangement in connection with typewriter construction for the purpose of selecting the desired keys with greater facility than if all of the keys were in the same 95 plane.

As shown in Fig. 1, all of the keys to the left of the dotted line 5, 5 are arranged in the manner common to typewriters, this arrangement of the letters being known as the 105 universal keyboard. It is to be noticed in the keyboard shown that an extra key is provided in each row at the right hand end of the row. These extra keys are shown at 1^a, 2^a, 3^a and 4^a, respectively. As indicated 110 in Fig. 2, the keys 1^a, 2^a, 3^a and 4^a occupy positions somewhat lower than the remaining

keys in the several rows 1, 2, 3 and 4 respectively, all of the keys in each of such rows being on the same level with the exception of the right hand keys mentioned.

- 5 As a result of the arrangement just described, the fingers of the operator, when resting upon the keyboard and seeking their proper position relatively thereto by feeling for the end keys of the several rows, would 10 naturally select the keys immediately to the left of the broken line 5, 5, since the extra keys 1^a, 2^a, 3^a and 4^a are sufficiently depressed to prevent their coming in contact with the fingers of the operator during the 15 normal operation of the machine. The characters controlled by the extra keys are used but seldom, and it requires little effort therefore to glance at the keyboard to select the proper one of these extra keys and operate 20 it when one of these extra characters is required. As a result, the extra characters are nearly or quite as available as though they were on the same level as the remaining keys of the corresponding rows, and the confusion 25 which would result from displacing the entire touch system of the right hand one key to the right is entirely avoided.

In the drawings there are shown, in addition to the regular operating keys described, 30 the usual shift keys 6, a shift lock 7, a back spacer 8, tabulating keys 9, and space bar 10. These last mentioned parts, however, are shown only to complete the layout of the keyboard and do not constitute any part of 35 the present invention.

- Figs. 3 and 4 show in detail a convenient means by which the right hand key of each row may be located lower than the remaining keys in the corresponding row. The 40 key bar 4^c, shown in Fig. 4, may be taken, for example as illustrative of the key bars used in connection with the row of keys 4, while the key bar 4^b used with the key 4^a may be of the same conformation, with the 45 exception that the vertical member or shank extending from the key bar to the key may be made sufficiently shorter to give the desired depression to the key 4^a relatively to the remaining keys 4 of the row.
- 50 While I have shown my invention in the particular embodiment herein described, I do not, however, limit myself to this exact construction, but desire to claim any equivalent that may suggest itself to those skilled 55 in the art.

What I claim is:

1. A typewriter keyboard consisting of four rows of keys arranged in different horizontal planes, the end key of each of such

rows being normally disposed below the 60 level of the remaining keys of such row.

2. In a typewriter, a keyboard consisting of regular keys arranged in transverse rows and extra keys also in such rows, the extra keys of each row being located below the adjacent 65 regular keys of the same row.

3. In a typewriter, a keyboard consisting of regular keys arranged in transverse rows, each row being in the same horizontal plane, and extra keys also in such rows, each of 70 said extra keys being in a different horizontal plane from the regular row with which said key is associated.

4. In a typewriter, a special keyboard consisting of a universal keyboard arranged 75 in transverse rows and extra keys also in such rows, said extra keys of the same row being located below the keys of the universal keyboard.

5. In a typewriter, a special keyboard 80 consisting of a universal keyboard arranged in transverse rows and extra keys also in such rows, each of said extra keys being on a different level from the row of regular keys with which it is associated. 85

6. In a typewriter, a special keyboard consisting of a universal keyboard arranged in transverse rows, each row being in a single horizontal plane and extra keys at the ends of such rows, each extra key being in a 90 lower horizontal plane than the row of regular keys with which said extra key is associated.

7. A typewriter keyboard consisting of a plurality of transverse rows of keys, the end 95 key of one of such rows being normally on a lower level than the remaining keys of such row.

8. In a typewriter, a keyboard consisting of regular keys arranged in transverse rows, 100 and extra keys also in such rows, said extra keys of each row being located at different levels from the adjacent regular keys of the same row.

9. In a typewriter, a keyboard having the 105 printing keys most used arranged in a plurality of rows, each of said rows lying in substantially a single horizontal plane different from the planes of the other rows, the remaining keys supplementing said rows but 110 lying in still other planes.

In witness whereof, I hereunto subscribe my name this 7th day of October A. D. 1908.

LYNN A. WILLIAMS.
